CLAIM

We claim, the ornamental design for a urinary catheter, as shown and described.

DESCRIPTION

FIG. 1 is a front perspective view of a urinary catheter.

FIG. 2 is a front elevational view thereof.

FIG. 3 is a rear elevational view thereof.

FIG. 4 is a right-side elevational view thereof.

FIG. 5 is a left-side elevational view thereof.

FIG. 6 is a top plan view thereof.

FIG. 7 is a bottom plan view of the thereof; and,

FIG. 8 is a rear perspective view of thereof.

The break lines in FIGS. 1 and 4-8 indicate that the appearance of any portion of the urinary catheter between the break lines forms no part of the claimed design.

The broken lines in FIG. 3 depict portions of the urinary catheter that form no part of the claimed design.
